UNITED STATES PATENT OFFICE.

HOWARD W. FLAGG, OF YONKERS, NEW YORK.

FELTING FUR BODIES.

SPECIFICATION forming part of Letters Patent No. 444,209, dated January 6, 1891.

Application filed May 12, 1890. Serial No. 351,529. (No specimens.)

To all whom it may concern:

Be it known that I, HOWARD W. FLAGG, of Yonkers, in the county of Westchester and State of New York, have invented a new Im-

5 provement in Felting Fur Bodies; and I do hereby declare the following to be a full, clear, and exact description of the same.

My invention relates to an improved method of felting fur bodies and particularly fur-
10 hat bodies, the objects being to prevent them from being broken or injured during the felting process and to do the work more economi-
cally than it heretofore has been done.

With these objects in view my invention
15 consists in a method of felting fur-hats or other fur-bodies, consisting in working them in a fulling-mill together with a padding of other fibrous stock, preferably, but not neces-
sarily, in the form of wool-hat bodies, which
20 in this case will be felted at the same time.

I prefer to carry out my invention by plac-
ing, say, equal numbers of fur and wool hat
bodies together in a fulling-mill of any ap-
proved construction and felting the two kinds

25 of bodies simultaneously, whereby the tender
fur-hat bodies are prevented from being torn or injured under the action of the hammers of the fulling-mill by the tougher wool-hat bodies which form a padding for them. But

30 for the padding action of the wool-hat bodies the fur-hat bodies would be torn and injured, and particularly when first placed in the mill, when they are very tender. I have spoken of putting an equal number of fur and wool
35 hat-bodies in the mill; but the percentage of each may be varied, as found desirable. The

fur and wool hat bodies are simply thrown into the mill together without any relative arrangement and constantly shift about under the action of the hammers.

It is not essential that the protecting ele-
ment in the mill be in the form of wool-hat
bodies, for, if desired, other fibrous bodies may
be used in their stead. By preference, how-
ever, I employ wool-hat bodies, as an obvious
45 economy is secured by simultaneously felting
the two kinds of hat-bodies in the same mill;
nor is my invention limited to fur-hat bodies,
as other fur bodies may be felted in the same
way.

Having fully described my invention, what
I claim as new, and desire to secure by Let-
ters Patent, is—

1. A method of felting fur bodies, consist-
ing in working them in a fulling-mill, together
55 with other fibrous bodies employed, in suffi-
cient quantities to form a padding for them
and prevent them from being injured or torn
by the hammers of the fulling-mill, substan-
tially as described.

2. A method of felting fur-hat bodies, con-
sisting in working them in a fulling-mill si-
multaneously with wool-hat bodies employed
in sufficient quantities to form a padding for
the fur-hat bodies and prevent them from
65 being injured or torn by the hammers of the
fulling-mill, substantially as described.

HOWARD W. FLAGG.
